Patented Oct. 7, 1856.

Dec. 8th 13

N. S. Neder, of Troy, N.Y.
Assignor to
Graff, Reisinger, & Graff,
Letters Patent No. 843. Dated October 9, 1851.

The Schedule referred to in these Letters Patent and making part of the same.

To all whom it may concern,

Be it known that I, N. S. Neder, of the City of Troy, in the County of Rensselaer, and State of New York, have invented or produced a new and original design for cooking stoves, which I call the "Advance air-tight stove," and I do hereby declare the following to be a full, clear, and exact description thereof, reference being had to the annexed drawing forming part of this specification, in which:

Figure 1, is a representation of the front plate of the stove.

Figure 2, is a representation of the side plate of the stove.

My improved design consists of a series of scrolls and leaves surrounding an elliptical moulding, with a raised center forming the ornamental work on the doors of the stove, or panels, in places where there are no doors marked a, a, figures 1 & 2. These scrolls and leaves being surrounded by mouldings of the shape and pattern shown in the drawings. On the side plates of the stove, see figure 2, on the small panels above the doors, I place a

raised pattern, marked b, b, in figure 2.

What I claim as my invention, and desire to secure by Letters Patent, is the use of the patterns or devices (marked a, & b, in the several drawings), for ornamenting the side pieces, front, and back pieces of cooking stoves, in the manner shown in the accompanying drawings.

In testimony whereof, I have hereunto set my hand this thirty first day of May
A. D. 1856.
